(57) **CLAIM**

The ornamental design for a video game controller peripheral, as shown and described.

DESCRIPTION

FIG. 1 is a perspective view of a video game controller peripheral showing our new design;

FIG. 2 is a top plan view thereof;

FIG. 3 is a bottom plan view thereof;

FIG. 4 is a right side elevational view thereof;

FIG. 5 is left side elevational view thereof;

FIG. 6 is a front elevational view thereof;

FIG. 7 is rear elevational view thereof;

FIG. 8 perspective view thereof, shown in its environmental use;

FIG. 9 is a perspective view of a second embodiment of a game controller peripheral thereof;

FIG. 10 is a top plan view of FIG. 9;

FIG. 11 is a bottom plan view of FIG. 9

FIG. 12 is a right side elevational of FIG. 9;

FIG. 13 is a left side elevational view of FIG. 9;

FIG. 14 is a front elevational view of FIG. 9;

FIG. 15 is a rear elevational view of FIG. 9; and,

FIG. 16 is a perspective view of FIG. 9, shown in its environmental use.

The broken lines showing the environmental of human figure and electronic device are for illustrative purpose only. Other broken lines indicate the disclaimed portions of the design. None of the broken lines form part of the claimed design.
